UNITED STATES PATENT OFFICE.

DANIEL B. JACOBS, OF NEW YORK, N. Y.

CLIP.

1,113,010.

Specification of Letters Patent.

Patented Oct. 6, 1914.

Application filed November 18, 1913. Serial No. 801,626.

To all whom it may concern:

Be it known that I, DANIEL B. JACOBS, a citizen of the United States, and a resident of the city of New York, borough of Manhattan, in the county and State of New York, have invented a new and Improved Clip, of which the following is a full, clear, and exact description.

The object of the invention is to provide a new and improved clip more especially designed for use on swingletrees, doubletrees and similar devices, and arranged to permit of quickly and securely attaching the clip without requiring the services of a skilled mechanic, to securely hold the trace holder or the supporting link in position, and to allow of conveniently disassembling the parts for removal and replacement of a worn out part.

In order to accomplish the desired result, use is made of a clip band open at one side and adapted to be passed around the swingletree or a like device, the open sides of the clip band terminating in outwardly-extending flanges, of which one has a return bend to form a hook for the reception of the trace holder or supporting link, and a bolt passing through the flanges in the rear of the trace holder or ring.

A practical embodiment of the invention is represented in the accompanying drawings forming a part of this specification, in which similar characters of reference indicate corresponding parts in all the views.

Figure 1 is a perspective view of the clip as applied to a swingletree; Fig. 2 is an enlarged sectional side elevation of the same on the line 2—2 of Fig. 1; Fig. 3 is a cross section of the same on the line 3—3 of Fig. 2; Fig. 4 is an enlarged sectional side elevation of the strap or trace holder clip, the section being on the line 4—4 of Fig. 1; Fig. 5 is a cross section of the same on the line 5—5 of Fig. 4; and Fig. 6 is a cross section of one end of a metallic swingletree provided with the improved trace holder clip.

The wooden swingletree illustrated in Fig. 1 is provided at the middle with a supporting clip B and near each end with a trace holder clip C. The supporting clip B consists essentially of a clip band B' passed around the swingletree A and terminating in outwardly-extending flanges B², B³, of which the bottom flange B³ is provided with a return bend forming a hook B⁴ for en-

gagement by an attaching ring or link D adapted to engage the doubletree clip. A bolt E extends vertically through the flange B² and the free end of the hook B⁴ to screw into a threaded boss B⁵ arranged on the bottom flange B³. The bolt E passes in the rear of the ring or link D so as to securely hold the latter in position in the hook B⁴ but to allow free up and down swinging of the said link or ring. It will be noticed that on screwing the bolt E in place the clip band B' is firmly clamped in position on the swingletree A and at the same time the bolt E acts as a retainer for the link or ring D to hold the latter in position on the hook B⁴. When the bolt E is removed the hook or link B can be conveniently detached from the hook B⁴ and the band B' can be readily detached from the swingletree A.

In order to prevent the clip band B' from shifting laterally on the swingletree A the said clip band is provided with an inwardly-extending rib B⁶ engaging an annular groove A' formed in the peripheral face of the swingletree A. It will be noticed that when the bolt E clamps the band B' in position on the swingletree A then the rib B⁶ snugly fits into the groove A' thus holding the clip against lateral displacement on the swingletree A.

Each of the end clips C consists of a clip band C' fitting into an annular groove A² formed in the swingletree A near the corresponding end thereof, and the said clip band C' terminates in outwardly-extending flanges C², C³, of which the bottom flange C³ is provided with an integral return bent member forming a hook C⁴ for engagement by the ring of the trace or other part to be attached to the clip C. A bolt F passes through the flange C² and screws into a threaded boss C⁵ formed on the bottom flange C³ so that the band C' is firmly clamped in place in the groove A² of the swingletree A. It will be noticed that by reference to Fig. 4 the bolt F does not pass through the hook C⁴ as above described in reference to the clip B but extends a distance in the rear of the hook C⁴ so as to permit of conveniently hooking the trace ring in position on the hook C⁴. By fitting the clip band C' into the recess A² the clip is held against lateral movement, and the clip can be readily removed from the swingletree by unscrewing the bolt F to allow

of disengaging the clip band from the groove.

In case the swingletree is of metal, as shown in Fig. 6 for instance, use is made of 5 a tubular swingletree A³ having each outer end provided with a return bent exterior flange A⁴ against which abuts the clip band C' of the clip C, the clip band being held against lateral movement by a bolt H passing through the band and through the wall 10 of the tubular swingletree A³; otherwise the clip C is of the construction shown in Figs. 1, 4 and 5.

From the foregoing it will be seen that 15 by the arrangement described the clips can be readily placed in position without the aid of a skilled mechanic, and in case any one of the parts is worn out and needs replacement then the clip can be readily removed 20 for the purpose mentioned.

Having thus described my invention, I claim as new and desire to secure by Letters Patent:

1. A clip, comprising a band adapted to 25 be passed around a swingletree, doubletree or like device, the band terminating at one side in outwardly-extending flanges, of which one has a return bent portion to form a hook, a ring held in the said hook, and a 30 bolt engaging the said flanges and the said

hook, the bolt extending in the rear of the ring to lock the latter in place on the hook.

2. The combination with a swingletree, doubletree or like device having a peripheral groove, of a clip band surrounding the 35 said device and having an inwardly-extending integral rib engaging the said groove to hold the band against lateral movement, the band terminating at one side in outwardly extending flanges, of which one is provided 40 with a return bend to form a hook for the reception of a ring, and a bolt engaging the said flanges to hold the band clampingly in position on the said device.

3. As a new article of manufacture, a 45 whiffletree clip, consisting of a band-like clip having approximately parallel flanges of unequal length, the longer flange being bent inwardly to form a hook, the flanges and hook having registering openings, and 50 a bolt passing through the openings of the flanges and hook.

In testimony whereof I have signed my name to this specification in the presence of two subscribing witnesses.

DANIEL B. JACOBS.
